UNITED STATES PATENT OFFICE.

WILLIAM CHRISTIAN SIEVERS, OF NEW ALBANY, INDIANA.

BOTTLE WASHER.

Application filed January 26, 1923. Serial No. 615,138.

This invention relates to bottle washers, and more particularly to those designed for connection with a water faucet.

The object of the invention is to provide a washer of this character which may be quickly attached to a faucet without the use of a permanent connection, and when not designed for use, may be readily removed and laid away.

Another object is to provide a device of this character which is simple in construction and which is brought into operation by simply placing a bottle thereover and pressing it down.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a front elevation of a sink with this improved washer shown applied, parts of the sink being broken out, and

Fig. 2 is a longitudinal vertical section through the washer, the water supply device being broken off for convenience in illustration.

In the embodiment illustrated, the bottle washer constituting this invention comprises a supporting rod or post 1 designed to rest at its lower end on the bottom of the sink S and which carries at its upper end a tubular shell 2, here shown having threaded connection with the post 1. This shell 2 is provided in its opposed side walls with longitudinally extending slots 3 for a purpose presently to be described.

The upper end of the shell 2 is closed by a screw plug 4 which carries a pipe 5 equipped at its opposite ends with nozzles 6 and 7.

A plunger 8 is closely fitted in the shell 2 for sliding movement therein, and is equipped at its upper end with a rubber washer 9 designed to normally close the nozzle 7 at the lower end of the pipe 5. This washer 9 is secured to the plunger by a cap 10.

A coiled spring 11 is mounted in the shell 2 below the plunger 8, bearing at its lower end against a washer 12 mounted in the shell, and this spring normally exerts its tension to

force the plunger 8 upwardly to close the lower end of pipe 5.

A pin 13 extends transversely through the lower end of the plunger 8 and through the slots 3 in the shell 2 and is fixed at its opposite ends in the opposed side walls of a casing 14, which surrounds the shell 2 and is spaced laterally therefrom being sufficiently large to permit the wash water from the bottle to flow down therethrough between it and shell 2.

This casing 14 is open at its upper and lower ends and is provided at its upper end with an annular groove 15 to form a seat to receive the mouth of the bottle B to be washed.

The casing 14 is provided in its opposed side walls near its upper end with elongated openings 16 through which water supply pipes 17 and 18 are designed to extend, and which enter the shell 2 at opposite sides thereof at a point adjacent the nozzle 7, as is shown clearly in Fig. 2. These pipes 17 and 18 have right angular extensions 19 and 20 equipped at their free ends with sockets 21 which are designed to fit snugly around the mouth of the faucets F and F' for supplying hot and cold water respectively to the washer. These sockets 21 are suitably packed to provide a water-tight connection with the faucet.

In the use of this washer, the parts being in the position shown in Figs. 1 and 2, the bottle B to be washed is placed over the pipe 5 with the nozzle 6 extending up into the body of the bottle and with the mouth of the bottle seated in the groove 15. The water faucets, one or both, are then opened and pressure exerted on the bottle B sufficiently to move the casing 14 downwardly, carrying with it the plunger 8. This movement opens the nozzle 7 at the lower end of the pipe 5 and permits the water flowing in through the pipes 17 and 18 to pass upwardly through the pipe 5 into the bottle B being discharged through the nozzle 6 and enters the bottle under pressure, whereby the bottle is thoroughly washed. When it is desired to sterilize the bottle in addition to cleansing it, the cold water faucet may be cut off and hot water only supplied.

When pressure on the bottle B is relieved, the spring 11 will force the plunger 8 upwardly and close the nozzle 7 at the lower end of pipe 5, thereby cutting off the water supplied to the bottle. The water in the

bottle B will drain through the casing 14 into the sink and pass out in the usual manner.

From the above description it will be obvious that this washer may be quickly and easily applied to the faucets F and F' by merely engaging the sockets 21 with said faucets and when the device is not to be used, the sockets are removed from the faucets and the apparatus may be put away.

Such changes in the form, shape, proportion and other minor details of construction may be made as do not depart from the principle or sacrificing any of the advantages of the invention as claimed.

I claim:—

In a device of the character described, a tubular casing, said tubular casing having lateral elongated openings formed therein, a shell mounted within the casing and having

elongated openings, pipes extending through the elongated openings of the casing and terminating within the shell to supply fluid thereto, a pipe extending into the upper end of the shell and adapted to receive fluid from the shell, a plunger mounted within the shell, a pin supported by the casing and extending through the elongated openings of the shell, said pin having connection with the plunger to move the plunger when the casing is moved, said plunger adapted to normally engage the inner end of the last mentioned pipe to cut off the supply of fluid therethrough, and a coiled spring engaging the plunger for normally holding the plunger in its inactive position.

In testimony that I claim the foregoing as my own, I have hereto affixed my signature.

WILLIAM CHRISTIAN SIEVERS.
